UNITED STATES PATENT OFFICE.

GEORGE LOOMS, OF MARKET HARBOUROUGH, ENGLAND.

TOE CASE, PUFF, OR THE LIKE FOR BOOTS AND SHOES.

1,015,500.

Specification of Letters Patent.

Patented Jan. 23, 1912.

Application filed August 4, 1910. Serial No. 575,498.

To all whom it may concern:

Be it known that I, GEORGE LOOMS, a subject of the King of Great Britain, residing at Market Harborough, in the county of 5 Leicester, England, have invented certain new and useful Improvements in or Relating to Toe Cases, Puffs, or the Like for Boots and Shoes, of which the following is a specification.

- 10 This invention relates to toe cases, toe boxes or puffs for boots and shoes of the type consisting of a combination of resilient and non-resilient materials, the resilient material being employed to maintain the shape 15 of the toe of the boot or shoe and the non-resilient material being used as a backing for the toe case and also to facilitate the lasting in of the toe during the manufacture of the boot or shoe.
- 20 The invention comprises a specific construction and combination of resilient and non-resilient materials arranged in such a manner as to produce a toe having a bold, sustained and rigid front end and upper 25 part and a light flexible yielding and resilient rearward part adjacent to where it is attached to the vamp of the upper.

The term "rigid" is intended to mean that the toe cap appears to possess all the 30 qualities of an ordinary solid box (leather) toe, firm to the touch, not easily indented when pressure is applied thereto, but having the exceptional and valuable feature that if from accident or otherwise it should be 35 crushed by a weight or force stronger than its normal power of resistance it will recover itself and regain its ordinary contour and appearance.

In describing the details of the invention 40 reference will be made to the accompanying drawing, in which:

Figure 1 is a view of the inside or under-side of a blank formed according to this invention. Fig. 2 is an outside or upper 45 view of the same. Fig. 3 is a section of the blank taken on the line $x-y$ of Fig. 2. Fig. 4 is a vertical section taken through the toe of a boot or shoe and showing the improved toe case, box or puff in place in said 50 toe.

The improved toe case comprises two or more layers or blanks (preferably two) consisting of resilient material, as indiarubber, and of non-resilient material, such as leather,

said layers being united by means of adhesive or cement, such for example as rubber solution.

The specific construction and combination of resilient and non-resilient materials preferably employed to produce the improved 60 toe case according to this invention comprises, as shown in Figs. 1, 2 and 3, a layer or blank 1 of indiarubber and a layer or blank 2 of leather. The two layers or blanks 1 and 2 are, before uniting, placed in juxtaposition so that the end 3 of the non-resilient 65 layer 2 protrudes beyond the resilient layer 1 at the toe, for lasting purposes, and the resilient layer or blank 1 projects beyond the non-resilient layer 2 at the opposite end 70 4 where the toe case joins, or is adjacent to, the vamp of the upper.

The indiarubber or resilient blank or layer 1 may be thickened at the center 5 (Fig. 3) which is to form the summit of the 75 toe when completed and it is reduced in thickness therefrom in all directions toward its outer edge.

When the improved toe case is in place in the toe of a boot or shoe as shown in Fig. 80 4, the non-resilient portion 2 of the case or puff will impart to the toe a bold, sustained and rigid front end and upper part a ; the resilient part 1 of the toe case will render the rearward part b of the toe of a light 85 flexible yielding and resilient nature; and the thickening 5, reinforced by the non-resilient material 2, imparts a rigid yet resilient character to the toe at its summit c .

The resilient blanks or layers 1 may be 90 molded in series with thick centers and thinner surrounding areas and subsequently cut up into units to be affixed to the backing or non-resilient layer 2 in the manner hereinbefore described.

The toe case blank is, as shown in Figs. 1 to 3, formed in a flat condition and the advantage of this is that such blank may be lasted to any shape of toe.

What I claim then is:

1. A box for the toes of shoes, comprising a piece of non-resilient material and a piece of resilient material united together by adhesive on a transverse line coincident with the summit of the toe, the edge of the resilient material overlapping the edge of the non-resilient material, and the two edges being correspondingly chamfered and form-

ing a smooth joint, both of said pieces being gradually reduced in thickness from the joint portion to their opposite edges.

2. A box for the toes of shoes, composed of a piece of stiff leather and a piece of soft rubber, having overlapping oppositely bevelled contacting edges secured together by adhesive material, the joint formed by the overlapping edges lying at approximately

the summit of the toe of the shoe and extending transversely thereof.

In testimony whereof I affix my signature, in presence of two witnesses.

GEORGE LOOMS.
